ATTORNEY

UNITED STATES PATENT OFFICE

EDWIN S. PATTERSON, OF SHARON, PENNSYLVANIA

WATER ELEVATOR

Application filed February 20, 1930. Serial No. 429,859.

This invention relates to liquid elevating devices of the type in which the jet of compressed air or other gas under pressure is utilized to elevate and discharge the liquid.

I am aware that ejectors employing a jet or jets of air or steam under pressure have been employed to blow liquid and other fluid materials through pipes. Such devices, however, have required a relatively large volume 10 of air or steam sufficient to impart a high velocity to the liquid or other material being conveyed and to maintain a high velocity of flow to the discharge outlet.

I am also aware that water and other liquids have been elevated by air-lift pumps in which a column of liquid is caused to rise through a pipe due to a differential pressure exerted on the ends of a column of liquid in the pipe. The differential pressure may be 20 created by exerting a pressure greater than atmospheric pressure on the body of liquid with which the lower end of the elevating pipe communicates or by exhausting air from the upper end of the pipe. In either case, in 25 air-lift pumps, it is common practice to inject air into the lower end of the column of liquid to create a continuous flow of air upwardly through the liquid, the upwardly moving bubbles of air, by reason of their 30 buoyancy lightening the column and increasing the height to which the column is raised by the differential air pressure.

Ejectors such as above described are very wasteful of power by reason of the high velocity of discharge and the large volume of compressed air required to convey a given amount of liquid and are further objectionable for the reason that the liquid is delivered in a spray, the water and air being thoroughly 40 mixed and the water being discharged in particles commingled with a relatively large volume of rapidly moving air.

Both jet ejectors and air life pumps are far from satisfactory in operation by reason 45 of their tendency to operate with a hammering action caused by periodic fluctuations in pressure with the result that the water or other liquid flows from the discharge end of the conduit in spurts rather than in a steady 50 stream.

The present invention has for its object to provide a jet operated liquid elevating device which requires a minimum volume of compressed air or other gas, which delivers the liquid from the discharge outlet in a steady 55 stream and at low velocity without any appreciable hammering action.

A further object is to provide an air jet elevator in which a kinetic energy of the air jet is utilized to impart velocity to the liquid 60 entering the pipe and to develop a continuous pressure head in the lower portion of the elevating conduit sufficient to maintain a continuous and uniform flow of liquid through the conduit and in which the buoyancy of the 65 air stream flowing centrally through the liquid column serves to increase the height to which the column may be elevated by the hydrostatic pressure developed by the jet.

With the above and other objects in view, 70 the invention may be said to comprise the device as illustrated in the accompanying drawings hereinafter described and particularly set forth in the appended claims, together 75 with such variations and modifications there- of as will be apparent to one skilled in the art to which the invention appertains.

Reference should be had to the accompanying drawings forming a part of this specification in which:

Figure 1 is an axial section through a liquid elevating device embodying the invention.

Fig. 2 is an enlarged axial section through the combined suction and pressure developing section at the lower end of the conduit.

Referring to the accompanying drawings the elevating conduit is in the form of a vertically disposed pipe 1 which may be formed in the usual manner of sections of pipe of suitable length coupled together. To the 80 lower end of the pipe 1, there is attached a tapering pipe 2 which tapers at a small angle from its lower to its upper end. The upper end of the tapering pipe 2 is of less diameter than the internal diameter of the pipe 1 and 85 extends into the lower end of the pipe 1, the tapered pipe 2 being attached to the pipe 1 by means of a suitable coupling sleeve 3 which is welded or otherwise rigidly attached to the pipe 2 and which has an internally 90 95 100

threaded upper end portion to receive the threaded lower end of the pipe 1. At its lower end, the tapered pipe 2 is of a diameter somewhat greater than the pipe 1 and has attached thereto a short pipe section 4 to the lower end of which is connected a perforated strainer section 5 which is connected to the pipe 4 by means of a sleeve coupling 6. An elbow fitting 7 is mounted in the pipe section 4, one end of the fitting being disposed axially of the pipe section 4 and the other extending through the wall of the pipe section. The elbow fitting 7 is coupled to a pipe 8 which extends from a suitable pressure tank or other source of air under pressure.

15 A nozzle 9 is secured to the inner end of the fitting 7 and extends upwardly therefrom axially of the tapered pipe. The nozzle 9 has a tapering upper end with a small discharge orifice 10 through which a fine jet of air may be discharged axially through the tapered pipe 2. The pipe 8 may be provided with a suitable control valve 11 for regulating the pressure of the air discharged through the nozzle 9.

20 The cross sectional area of the orifice is very small with respect to the cross-sectional area of the pipe 2 at the level of the orifice. The size of the orifice 10 will depend to some extent upon the height to which the liquid is elevated, the size of the orifice being slightly increased for higher lifts.

25 In all cases, however, the cross-sectional area of the nozzle orifice will be a very small fraction of that of the tapered pipe at the level of the orifice. The distance from the discharge orifice 10 of the jet nozzle to the upper end of the tapered pipe 2 is also important, since it has been found that hammering action will occur if the jet orifice be shifted too far away from the outlet end of the tapered pipe or too close to said end.

30 It is desirable that the air be discharged through the tapered pipe at a high velocity and the air should therefore be under considerable pressure. It has been found that the jet operates very efficiently with a pressure of approximately 100 pounds. This pressure can be reduced considerably by adjusting the valve 11 to slow down flow of water from the outlet.

35 A jet of air under relatively high pressure will be discharged from the small orifice 10 at an extremely high velocity, reducing the pressure within the tapered pipe 2 so that liquid will rise to the level of the jet orifice.

40 The rapidly moving air jet entrains the liquid and causes it to flow with gradually increasing speed to the upper end of the tapered pipe 2. The velocity of the air stream is such that the air remains in a central column while the water flows in a tubular column surrounding the air. The air stream delivered into the lower end of the pipe 1 still possesses considerable kinetic energy

which is imparted to the liquid through which the air flows and the air stream continues upwardly through the pipe 1 at the center of the liquid column. The liquid delivered from the upper end of the tapered pipe 2 has considerable kinetic energy due to the velocity imparted to it by the air jet and this energy is exerted in the form of hydrostatic pressure on the column of liquid in the pipe 1, this pressure being sufficient to force the liquid in the pipe 1 to a considerable height. It will be apparent that the air stream flowing centrally through the liquid column in the pipe 1 materially lightens this column and increases the height to which a given hydrostatic pressure will raise the liquid. As herein shown, the nozzle orifice 10 is positioned at substantially $\frac{1}{3}$ the distance between the lower and upper ends of the pipe 2. The pipe 2 has a diameter at its upper end which is substantially one-half the diameter of its lower end. The pipe 1 is of an internal diameter slightly greater than the diameter of the upper end of the tapered pipe.

45 It has been found that with an elevating pipe $1\frac{1}{4}$ inches in diameter, the tapered pipe may be of substantially 1 inch in diameter at its upper end, 2 inches in diameter at its lower end, and substantially 12 inches in length. The orifice 10 may be positioned substantially 8 inches below the upper end of the tapered pipe and the diameter of the orifice may be from $\frac{3}{16}$ of an inch to $\frac{1}{8}$ inch. The air is preferably delivered to the nozzle at a relatively high pressure, 100 pounds or over for most efficient operation, although the pump will still operate at a considerably reduced pressure, the flow of liquid being correspondingly reduced. The pipe 8 leads from a high pressure tank and if at any time it is desired to reduce the rate of flow of water or other liquid being lifted, this may be done by partially closing the valve 11.

50 If desired, the liquid may be discharged from the open upper end of the elevating pipe 1 in which case the air carrying some fine particles of liquid is discharged centrally of the water column while the water flows uniformly in all directions over the upper edge of the pipe. It is generally preferred, however, to discharge the liquid through a suitable spout and in this case, it is desirable that suitable means be provided for permitting the air to be discharged separately from the water.

55 As herein shown, a suitable cylindrical chamber 12 is attached to the upper end of the pipe 1, being provided with an opening in its bottom to receive the pipe 1. The chamber 12 has perforations 13 in the upper portion of its side wall and is provided at its bottom alongside the pipe 1 with a discharge spout 14. The perforated upper portion of the chamber 12 is enclosed by an outer casing 15 which has a fluid tight fit

around the chamber 12 below the perforations 13 and which is provided with a central air outlet 16 at its upper end.

In the operation of the pump, the liquid 5 rising in the pipe 1 flows laterally into the bottom portion of the chamber 12 and is discharged through the spout 14. The air carrying fine particles of liquid is carried upwardly into the upper portion of the chamber 10 12 where the liquid collects on the walls of the chamber and the air escapes laterally through the opening 13 into the chamber 15 and through the discharge opening 16. Any liquid accumulating on the wall of the chamber 15 flows downwardly to the bottom of the chamber and any liquid deposited in the outer casing 15 will collect in the bottom thereof and flow back into the chamber 12 through the perforations 13. The chambers 20 13 and 15 serve to effectually separate the air from the particles of liquid carried in suspension and to discharge the air and liquid separately without creating any appreciable back pressure on the liquid column in the 25 pipe 1.

It has been found that the device of the present invention operates to elevate water rapidly with a uniform flow and without any material fluctuations in pressure and that a 30 relatively small volume of air is required for the operation of the device.

It will be apparent that the present invention provides a very simple and efficient water elevating device which is inexpensive 35 to manufacture and which may be operated at small expense.

A further important advantage of the present invention is that rusting of the pipe through which the air and water is forced 40 is eliminated. It has been found that the air passes up in the center of the water column and does not come in contact with the pipe wall and that iron pipes may be used for long periods of time without rusting, 45 which has heretofore been considered an objectionable feature incident to the use of air jet ejectors and air lift pumps in which the walls of the pipe are continually subjected to the action of air and water and are consequently quickly rusted away.

It should also be noted that the device of the present invention elevates the liquid in a column which flows continuously substantially without fluctuation, the flow into the 55 inlet being uniform, the rate of flow increasing through the tapered pipe and decreasing in the elevating conduit into which the tapered pipe delivers. Consequently, there is very little agitation of the water or other 60 liquid at the inlet such as would tend to cause solid impurities to be drawn up with the liquid and very little tendency for the water to dislodge solid impurities such as rust from the walls of the pipe. The device of the 65 present invention is therefore well adapted

for use in elevating water from a well for household use or for handling any liquid where it is desired to deliver the liquid with as little sediment, rust or other solid impurities as possible.

What I claim is:

1. A device for elevating liquids comprising an upright pipe, a tapering pipe connected to the lower end of the first pipe coaxially therewith and having its outlet end 70 within the first pipe and of less diameter than said first pipe, and a jet nozzle disposed axially within the tapered pipe and having a small outlet at its upper end for delivering a fine jet of highly compressed gas axially 75 through said tapered pipe to entrain a column of liquid, impart velocity thereto and deliver the same under pressure into said upright pipe, said nozzle outlet having a cross-sectional area less than one-fiftieth of 80 that of the outlet end of said tapered pipe.

2. A device for elevating liquids comprising an upright pipe, a tapering pipe connected to the lower end of the first pipe coaxially therewith and having its outlet end 90

within the first pipe and of less diameter than said first pipe, and a jet nozzle disposed axially within the tapered pipe and having a small outlet at its upper end for delivering a fine jet of highly compressed air axially 95 through said tapering pipe to entrain a column of liquid, impart velocity thereto and deliver the same under pressure into said upright pipe, the cross sectional area of the nozzle outlet being a very small fraction of 100 the cross-sectional area of the outlet end of the tapered pipe and said nozzle extending into the lower end of the tapered pipe a distance approximately equal to one third the length of said tapered pipe.

3. The herein described method of elevating liquids with compressed gas which consists in directing a fine stream of highly compressed gas axially through an upwardly tapering pipe toward the upper outlet and 105 thereof at a velocity sufficient to maintain a central rapidly moving core of gas surrounded by a tubular column of liquid at the outlet end of the pipe.

4. The herein described method of elevating liquids with compressed gas which consists in directing a fine stream of highly compressed gas axially through an upwardly tapering pipe toward the upper outlet end thereof at a velocity sufficient to maintain a central rapidly moving core of gas surrounded by a tubular column of liquid at the outlet end of the pipe, and conveying the liquid and air from the upper end of said tapered pipe 110 through a stand pipe coaxial with the tapered pipe and of slightly larger diameter than the outlet end of the tapered pipe.

In testimony whereof I affix my signature.
EDWIN S. PATTERSON.
